Mark Ordway
ATTORNEY

UNITED STATES PATENT OFFICE.

ROBERT REINER, OF WEEHAWKEN, NEW JERSEY.

FABRIC-WINDING MECHANISM.

Application filed October 31, 1921. Serial No. 511,721.

To all whom it may concern:

Be it known that I, ROBERT REINER, a citizen of the United States of America, and a resident of Weehawken, county of Hudson, and State of New Jersey, have invented certain new and useful Improvements in Fabric-Winding Mechanism, of which the following is a specification.

The present invention relates to fabric winding mechanism of embroidering machines or the like and has for its object to provide an improved construction whereby the fabric roller can be readily disconnected from the feeding mechanism and be turned by hand to wind up the fabric to be embroidered or remove the finished embroidery from the roller.

It has been found that with the large embroidering machines generally of about 15 yards length the winding up of a piece of fabric and the removal of the finished fabric from the fabric roller by means of the feeding mechanism is objectionable because when the fabric during either of such operations becomes caught the operator is unable to discover this, since the resistance offered to the feeding mechanism by the caught part of the material is too small to be noticeable and caution the operator of any irregularity in the operation, with the result that the material is torn. Therefore, it is preferred to wind up and off the material by hand which enables the operator to feel with his hands the slightest resistance and remove the same before any damage occurs. But with the winding mechanism of ordinary construction the turning of the fabric roller by hand is very difficult, if not utterly impossible, and can be done only very slowly entailing considerable loss of time owing to the friction between the meshing gears of the winding mechanism, and to some parts, such as ratchet and pawl, that have to be disengaged to permit the roller to turn in the reverse direction, being not very easily accessible.

These difficulties are overcome according to my invention by arranging one of the gears of the winding mechanism on a longitudinally displaceable shaft so that whenever the roller is to be turned by hand the said gear can be simply moved out of mesh with the other gear thereby releasing the

roller to be free to be turned in both directions.

This invention will be more fully understood by reference to the accompanying drawing in which similar characters denote corresponding parts and in which Fig. 1 is a front elevation of the fabric winding mechanism of an embroidering machine with some parts shown in section, and Fig. 2 an inner end view thereof with the fabric roller removed.

In the drawing *a* denotes the fabric frame and *b* the bearings in which is rotatively supported a shaft *c*. The shaft *c* extends outwardly through the frame and on its projecting end, *c'* carries a gear *d* suitably fixed thereon. The gear *d* is provided centrally with an oblong projection *e* of rectangular shape to engage between two ear like members *f* projecting from the end of the fabric roller *g*. The opposite end (not shown) of the roller may be constructed and supported in a similar way. The end *c'* of the spindle *c* is extended to project through a central bore *g'* into the roller *g*.

In bearings *h* of the frame is supported a second spindle *i* parallel to the spindle *c* which also is extended to project outwardly from the frame toward the roller *g*. On the outer end of the spindle is fixed a smaller gear *j* which is capable of meshing with the larger gear *d* to transmit motion to the roller for feeding the latter during the embroidering operation. The spindle *i* also carries the ratchet wheel *k* with which cooperates the pawl *l* (Fig. 2), said ratchet and pawl constituting part of the roller feeding mechanism. The spindle *i* is so supported in the bearings *h* as to be longitudinally displaceable. The ratchet wheel is adapted to be held against axial displacement by its hub *k'* being mounted between the lateral bearings *h* and is rotatively connected to the shaft *i* by a key *m* engaging a longitudinal groove *i'* in the spindle *i*.

Owing to the spindle *i* being displaceable longitudinally it is possible whenever it is desired to wind a piece of fabric around the roller or remove the finished goods from the latter to simply pull the small gear out of mesh with the larger gear into the position indicated by dotted lines (Fig. 1) thereby releasing the roller *g*. A stop *o* in form of a

pin or the like may be provided on the spindle *i* which when the spindle is displaced will abut against the hub *k'* and prevent the spindle from being removed entirely from its bearings.

What I claim is:—

1. In a fabric winding mechanism for embroidery machines or the like, the combination with the fabric roller, rotary shaft, 10 ratchet and pawl cooperating with the latter, of a pair of intermeshing gears for feeding said roller during the embroidery operation, of which gears one is mounted on said rotary shaft and operatively connected to 15 said roller, a longitudinally movable shaft on which the second of said gears is fixed, said shaft having a longitudinal groove, a key in said groove to engage the ratchet mounted on said second shaft and a stop 20 for limiting the longitudinal displacement of said second shaft.

2. In a fabric winding mechanism for embroidery machines or the like, the combination with the fabric roller, of a rotary shaft, a gear fixed on said shaft and having 25 a projection, said roller having ears engaging said projection, a longitudinally displaceable shaft a ratchet thereon, a pawl cooperating with said ratchet and a gear fixed to said displaceable shaft to mesh with 30 said first named gear, said last named gear being capable of being brought out of mesh with said first named gear by displacing said second shaft to enable the turning of the fabric roller by hand. 35

Signed at Weehawken, N. J., this 28th day of October, 1921.

ROBERT REINER.
